INVENTOR

ATTORNEY.

UNITED STATES PATENT OFFICE.

HARVLIN PADDOCK, OF ST. JOHNSBURY, VERMONT, ASSIGNOR TO THE E. & T. FAIRBANKS & COMPANY, OF SAME PLACE.

SCALE.

SPECIFICATION forming part of Letters Patent No. 595,200, dated December 7, 1897.

Application filed April 27, 1897. Serial No. 634,148. (No model.)

To all whom it may concern:

Be it known that I, HARVLIN PADDOCK, a citizen of the United States, residing at St. Johnsbury, in the county of Caledonia, State of Vermont, have invented certain new and useful Improvements in Scales, of which the following is a description, reference being had to the accompanying drawings, and to the letters of reference marked thereon.

10 My invention relates to an improvement in postal scales, and particularly to a scale of that class in which a revolving beam is provided on its opposite sides with graduations indicating in cents the postage required for 15 letters, books, printed matter, newspapers, periodicals, and merchandise.

The object of the invention is to provide a simple device by the use of which a person can tell at a glance, knowing the character of 20 the article being weighed, just how much postage will be required.

Heretofore it has been proposed, as shown 25 in the patent to Fairbanks, No. 203,902, to provide a revolving scale-beam having different graduations on its opposite sides, one set being divided according to the metric system into gram rates, while the opposite side is graduated in the English system of ounces and fractions thereof. It has also been pro- 30 posed, as shown in Patent No. 421,026, granted February 11, 1890, to Bitschofsky, to provide in connection with the scale-beam a postal-scale card supported on the beam at one side thereof, said card containing separate longi- 35 tudinal columns devoted to the four different classifications of postage, with the amount of postage required per ounce, with a statement at the end of the column of the particular class of postage and the kind of matter com-

40 prised therein, and in connection with this is used a poise having a pointer rigidly fixed on the poise and extending over the graduated face of the card. This is objectionable in that it adds considerable weight to the scale-beam, 45 which additional weight must be remedied by proper rebalancing. It has also been proposed in a grain-scale beam, as shown in patent to Braley, No. 509,591, to provide in addition to the graduated beam a revolving 50 scale-rod upon which are marked scales of

different graduations, according to the kind of grain being weighed.

The present invention is an improvement on the device shown in the Fairbanks patent and is different from the devices shown in the other patents in that it is far less complicated than said devices referred to, is neater in appearance, has not so many parts liable to get out of order, and contains features of difference which will be clearly shown and de- 60 scribed.

The invention consists in the matters hereinafter described, and referred to in the appended claims.

The invention is illustrated in the accom- 65 panying drawings, in which—

Figure 1 is a side elevation of a postal scale constructed in accordance with my invention. Fig. 2 is a top plan view of the beam and poise, part being broken away. Fig. 3 is an 70 elevation of the beam, showing the side opposite to that shown in Fig. 1.

In the drawings, A represents a beam supported and revolving in a manner similar to that shown in the Fairbanks patent above 75 referred to. B represents a poise-slide thereon; C, the supporting-base of the scale.

D is the scale-pan; E, the article to be weighed; F, the connection between the beam and the beam-supporting part I, which connection F is formed so as to allow of rotation of the beam, and J is a spring-catch which is fixed to the fulcrumed part I and holds the graduated beam when rotated to either one side or the other.

85 The beam A is graduated on its upper edge, indicating ounces, whereby the weight of any small article in fractions of a pound may be determined. Upon one face said beam is graduated at the top corresponding to the division into ounces, but the numbers placed beneath said graduations represent the number of cents required as postage on merchandise matter. On the lower part of the same side of the beam the graduations are noted 90 for every four ounces, and the numbers attached to each one of these graduations indicate the amount of postage required for newspapers and periodicals. Upon the other side 95 of the beam the graduations are for every 100

ounce, but the numbers applied thereto represent the amount of postage required for letters, while upon the same side of the beam upon the lower edge the graduations are every 5 two ounces, and the numbers represent the amount of postage required for books or other class of articles where the postage is one cent for each two ounces.

The poise which slides on the beam is provided with readings upon opposite sides, the reading upon the top of one side being "Merchandise," this corresponding and being arranged adjacent to the numbers representing the rates of postage on merchandise. On the 10 same side and on the lower part of the poise are the words "Newspapers" or "Newspapers and periodicals," these being arranged adjacent to the numbers representing the amount of postage required on such articles. On the 15 other side of the poise are arranged in corresponding positions to their respective money values the words "Letters and books" or "Books and printed matter." It will be seen that this presents a very simple and neat scale 20 for the work designed. For example, suppose a package containing merchandise is to be weighed. The same is placed on the pan and the beam, if necessary, is rotated to bring the side of the poise containing the word 25 "Merchandise" to the front. The poise is then moved along until the scale balances,

when the figure adjacent the word "Merchandise" will indicate exactly the amount of postage required, and so on through all the four classes of mailable articles.

35

Having thus described my invention, what I claim, and desire to secure by Letters Patent, is—

1. A postal scale comprising a revolving beam having figures on both sides indicating 40 money values of different classes of postal matter and a poise sliding on said beam and having readings on both sides, indicating the character of article weighed, said readings being arranged adjacent to the line of figures 45 which indicate the amount of postage required for the article in that particular class which is being weighed, substantially as described.

2. A postal scale comprising a revolving beam having figures on both sides indicating 50 money value of different classes of postal matter and having markings upon the edge indicating divisions of pound and a poise sliding on said beam and having readings on both sides indicating classes of mailable articles, 55 substantially as described.

In testimony whereof I affix my signature in presence of two witnesses.

HARVILIN PADDOCK.
